UNITED STATES PATENT OFFICE.

AUGUST HARDING, OF OAKLAND, CALIFORNIA.

DYNAMO-ELECTRIC MACHINE.

SPECIFICATION forming part of Letters Patent No. 385,458, dated July 3, 1888.

Application filed June 11, 1887. Serial No. 241,076. (No model.)

To all whom it may concern:

Be it known that I, AUGUST HARDING, of 5
Oakland, county of Alameda, State of California, have invented an Improvement in Dyna-
mo-Electric Machines; and I hereby declare
the following to be a full, clear, and exact de-
scription of the same.

My invention relates to certain improve-
ments in the construction of dynamo-electric
machines; and it consists of certain details,
which will be more particularly described by
reference to the accompanying drawings, in
which—

Figure 1 is vertical elevation of the half of
15 the machine below the horizontal axis and a
vertical central section of the half above the
axis. Fig. 2 is a transverse vertical section
taken through the revolving armature. Fig.
20 3 is an enlarged perspective view of one bar
of the commutator. Fig. 4 is an enlarged per-
spective view of the commutator. Figs. 5 and
6 are front and rear end views of the armature,
showing its attachment to the spider.

The object of my invention is to provide an
improved and convenient construction of the
frame of the revolving armature and of the
commutator-sections, so that the parts may be
easily separated or assembled. The different
30 parts of the armature are perfectly and com-
pletely separated from each other, and the
commutator by its construction overcomes the
common difficulty of short-circuiting.

A is the horizontal shaft, which extends
through and is supported upon the frame-work
35 B, being properly journaled at opposite ends.
These ends are made separate from the hori-
zontal portions which carry the field-magnets,
and are bolted to them, as shown.

C C are the "field-magnets," so called, the
40 coils of which are wound upon the horizontal
bars D to any desired thickness, although in the
present case I have only shown one layer each
for the field-magnets and for the revolving
armatures.

45 E is the spider, which is made of any non-
magnetic materials, as brass or bronze, and is
keyed upon the shaft A, so that its arms pro-
ject radially and serve to support the rings of
which the armature is formed. Upon the ends
50 of the arms E of the spider are formed the seg-
mental plates F, and upon the exterior of these

plates is placed a non-conducting substance,
G. The rear end of the spider has the arms
turned up, as shown at H, to serve as an abut-
ment against which the rings I are supported, 55
and also to serve as an attachment to receive
the screw-bolt which enters these arms, and
thus holds the rings in place.

The rings I, of which the armature is formed,
slip over the arms of the spider, the rear or 60
inner one abutting against the upturned ends
H, and the others following in succession, as
shown in Fig. 1, until the outer or front end
has been reached. The outer ring is formed
with inwardly-projecting lugs J, which enter 65
corresponding notches in the end F, and thus
prevent them from turning round. The bolts
K are then passed through the rings corre-
sponding in position with each of the arms E
of the spider, and the inner ends of the bolts 70
screw into the upturned ends H, as before de-
scribed. As the inner edges of these rings I
rest upon the insulating material G, which is
placed upon the segments F, it will be seen
that they are very perfectly insulated from the 75
spider and shaft and its connections.

The commutator is made as follows: Upon
the shaft A, near the rear end of the revolving
armature just described, is fixed a sleeve, L,
having the end nearest the armature turned 80
over to form a sort of cap, M, the interior of
which shows an inclined face. This cap may,
if desired, be made separate from the sleeve
and fixed thereto. Outside the sleeve L is a
second sleeve, N, the ends of which have a 85
smaller outside diameter than the central por-
tion, and upon these ends the slotted insulat-
ing-rings O are placed. The commutator-sections
P are made, as plainly shown in Figs.
3 and 4, having an upwardly-projecting arm, 90
Q, on each, to which the wires from the arma-
ture are soldered. The sections P are made
in the form of sectors in transverse section,
but the ends are made considerably narrower
than the central portion, as shown at R, and 95
these ends fit into and are supported by the
slotted insulating-rings O, before described.
When these sectors have been laid around the
central portion as closely together as it is in-
tended to have them stand, there will be con-
siderable spaces left between the extensions
R at each end, and this admits air between 100

these parts and prevents their becoming loaded with dust or foreign matter, so as to interfere with or spoil the insulation. These projecting ends R fit in the slotted insulating-rings 5 at the ends of the sleeve N, and the central portions of the sectors P are slightly separated from each other, so that as the commutator revolves the stationary brushes, which are supported upon the arms or holders S and which 10 rest upon the periphery of the commutator, will take the electric current from each of the sections successively as they pass. Outside of the ends R, which are beveled or inclined, as shown, are placed the insulating-pieces T, 15 and it will be seen that when the ends of the sectors P are forced into the cap M they will be firmly held in place and at the same time completely insulated. At the opposite end is a similar cap, U, which fits over that end of 20 the inclined portions R of the commutators, and the whole is forced together by means of a sleeve, V, which screws upon the inside sleeve, L, thus drawing the parts firmly together. This collar V may be held after being 25 screwed up by a set or lock nut, W. From the upright portion of the frame B a cone or tapering shell, X, extends toward the commutator a short distance and then has its end made cylindrical and extended parallel and 30 near the shaft, as shown at Y, and upon the outside of this sleeve are fixed the arms which support the brush-holders S. The conical portion of this shell, which increases in diameter toward the frame B, has an inclined duct or 35 passage, Z, connected with its lower portion, through which any oil which may fall from the journal-boxes will be carried off and discharged outside the machine, and thus prevented from falling upon the coils and spoiling 40 the insulation or doing other damage.

Having thus described my invention, what I claim as new, and desire to secure by Letters Patent, is—

1. In a dynamo-electric machine, the spider 45 formed of non-magnetic material having the radial arms of narrow cross-section in the direction of rotation, and having the expanded plates or segments at their outer ends with an exterior coating of insulating or non-conducting material, in combination with the independent armature rings or disks having 50 their peripheries resting upon the non-conducting material upon the exterior of the seg-

ments, and the insulating-wire wound around the disks, substantially as herein described. 55

2. The spider composed of radial arms having outwardly-turned portions at one end and provided with the cylindrically-curved segments extending from one end to the other of the arms, with an insulating material upon the 60 periphery of the segments, in combination with the independent rings or disks fitting outside the segments and separated therefrom by insulating material, the front end disk being provided with lugs which enter corresponding depressions at that end of the spider to prevent it from turning upon the same, and bolts extending through the rings and screwing into the upturned flanges at the rear end to hold them in place, substantially as de- 70 scribed.

3. A commutator consisting of independent sectors surrounding a common center, having the ends or extensions R made thinner than the central portion, with which the brushes 75 form contact, and slotted insulated rings supporting the ends, so that air-spaces are formed between them, substantially as described.

4. In a dynamo-electric machine, the commutator consisting of independent sectors having their ends reduced in the direction of the 80 commutator circumference and supported in slotted insulated rings, with insulating material upon the outside of these ends, in combination with a fixed hollow cap having an inclined inner face, in which one end of the sectors are forced, and a movable cap having an inclined inner face for receiving the opposite ends of the sectors, substantially as herein described. 85

5. Commutator-sections having tapered ends reduced in the direction of the commutator circumference, a fixed and a movable cup-shaped cap having each an inclined face for receiving the tapering ends, and the slotted 90 insulating-rings, in combination with a screw collar or sleeve bearing against the movable cap and locking and holding the sections in place, substantially as herein described. 95

In witness whereof I have hereunto set my hand.

AUGUST HARDING.
